P. GOLATZKY.
PULL ATTACHMENT FOR KEY SOCKETS.
APPLICATION FILED JULY 27, 1916.

Patented Aug. 28, 1917.

Werner Block

UNITED STATES PATENT OFFICE.

PHILIP GOLATZKY, OF NEWARK, NEW JERSEY, ASSIGNOR TO HARRY KRICH, OF NEWARK, NEW JERSEY.

PULL ATTACHMENT FOR KEY-SOCKETS.

1,238,401.

Specification of Letters Patent. Patented Aug. 28, 1917.

Application filed July 27, 1916. Serial No. 111,684.

To all whom it may concern:

Be it known that I, PHILIP GOLATZKY, a subject of the Czar of Russia, residing at Newark, Essex county, and State of New Jersey, have invented certain new and useful Improvements in Pull Attachments for Key-Sockets, of which the following is a full, clear, and exact description.

This invention relates to improvements in pull-devices for electric-light fixtures, the object being to provide a device that can be applied to the key of a key-socket electric-light fixture so as to transform it into a pull-socket. It oftentimes occurs that key-socket fixtures are located in inaccessible places or positions, making it extremely awkward to turn the current on and off. My improved attachment is designed to facilitate the manipulation of the switch or key on these inaccessibly located sockets, although it is also well adapted for application to key-sockets generally, providing, as it does, a more convenient manipulation to turn the current on or off. While my improved socket is positive in its action, it is made up of but few parts and can be cheaply manufactured and readily applied.

I will now proceed to describe my invention in detail, the essential features of which will be summarized in the appended claims, reference being had to the accompanying drawing, forming part hereof; wherein—

Figure 1 is a side elevation of a key-socket fixture having my pull device attached thereto;

Fig. 2 is an enlarged sectional detail plan view of my improved attachment;

Fig. 3 is a side elevation of my improved attachment, certain parts being omitted, the locking ring being shown in section;

Fig. 4 is a vertical sectional view, the section being taken on a line 4—4 in Fig. 2;

Fig. 5 is a similar view, the section being taken on a line 5—5 in Fig. 2;

Fig. 6 is a top edge view of the pawl-plate;

Fig. 7 is an enlarged vertical sectional view, the section being taken on a line 7—7 in Fig. 2;

Fig. 8 is a sectional top plan view of a modified form of my improvement;

Fig. 9 is a diagrammatic face view of the form shown in Fig. 8, illustrating the relationship between the pawl-plate and ratchet

elements; and

Fig. 10 is a top plan view of one form of bracket which I may employ.

Referring to the drawing, the numeral 11 indicates a socket having a key 12 acting as a switch, a portion of an electric-light bulb being indicated by 13. My improved pull-attachment, indicated generally by 14, comprises a clamp 15 carried by a spindle 16 which in turn is carried by a bracket 17 arranged for securing to the socket 11. Any form of bracket may be used, the one illustrated carrying a clamp 18 to engage the socket, a bolt 19 being employed to draw the members of the clamp firmly in contact with the socket. To operate or rotate the pull-attachment, I employ a ratchet-plate 21 and a pawl-plate 22 carrying a handle 23. The ratchet-plate 21 is provided with a series of recesses 24, one wall 25 of which is engaged by the pawls 27 carried by the pawl-plate 22. The pawls 27 are provided by bending out tongues formed in the plate 22, said tongues being formed by cutting slots 28 in said plate, as will be evident by an inspection of the drawing.

To secure the clamp 15 and ratchet-plate 21 to the spindle 16, I provide the spindle 16 with a slot 29, to form horns 30, and the ratchet-plate 21 with openings 31, 31 through which the horns 30 are passed (see Fig. 4) and through a central opening 32 in the clamp 15.

After having passed the horns through the openings 31, in the plate 21 and opening 32 in the clamp 15, they are bent upwardly and rearwardly against the clamp 15, as shown in Fig. 2. By the above described method, I am able to rotatably secure the clamp 15, ratchet-plate 21 and spindle 16 together.

The pawl-plate 22 is rotatably mounted on the spindle 16, but is kept pressed against the ratchet-plate 21 by a spring 33, one end of which is secured to the bracket 17 (see Fig. 7), the other end being secured to the ratchet-plate 22. The spring 33 is arranged to exert pressure against the pawl-plate 22 in one direction and against the head of the spindle 16 in the opposite direction.

To allow the clamp 15 and spindle 16 to rotate in but one direction, I provide a spring 34 which is tightly coiled around the spindle 16 (see Fig. 7). One end of the spring 34 is secured to the frame 17, the other end thereof being free. The spring 34

will allow the spindle 16 to be rotated in one direction, for instance the direction indicated by the arrow 35 in Fig. 7, but will prevent the said spindle from being rotated in the opposite direction, indicated by the arrow 36, as said spring will tighten and grip the said spindle should it tend to rotate in the direction of the arrow 36. When the spindle is rotated in the direction of the arrow 35, the spring 34 will expand. The spring 34 acts to grip and hold the spindle 16 against rotation during the return movement of the pawl-plate 22 after having been operated to advance the ratchet-plate 21 one step.

To apply the attachment, the clamp 15 will be slipped over the key of the socket and the locking-ring 37 moved along said socket to firmly cause same to grip the key 12. To turn the current on or off, the key 12 will be rotated in one direction only, not forward and then backward. Although the lever 23 and its pawl-plate will have a reciprocating motion, the movement imparted to the ratchet-plate and clamp will be intermittently rotatable. It will be apparent that the pawls 27 will engage the walls 25 of the recesses 24, as soon as they aline therewith, the spring 33 acting to cause said engagement. When the pawl-plate is returned, after having actuated the ratchet-plate and clamp, the ratchets 27 will jump out of their recesses 24, slightly compressing the spring 33, but will be forced into the recesses again as soon as alinement takes place.

In the form of device illustrated in Figs. 8 and 9, the spindle 37 consists of a cotter-pin which is passed through the central opening 38 in the pawl-plate 22 and central opening 32 in the clamp 15. After having been passed through the clamp 15, the ends of the members 39 and 40 of the cotter-pin are bent outwardly, then over the edge of the clamp, and then inwardly as shown in Fig. 8. The inwardly turned outer ends 41 of the cotter-pin members 39 and 40 constitute ratchet-members which are engaged by the pawls 27.

The spindle or cotter 37 is carried by a bracket consisting of a pliable wire 46 twisted around said cotter, as at 42. The end 43 of the bracket has secured thereto the spring 44 which performs the same function as the spring 34. A spring 45 in this latter form performs the same function as the spring 33 in the form illustrated in Fig. 2. The bracket or wire 46 is sufficiently pliable to be twisted around the socket to form a support.

Having now described my invention, what

I claim and desire to secure by Letters Patent is:

1. A clamp provided with a central opening, a rotatable spindle therefor passing through said opening provided with a slot longitudinally thereof to provide horns, a ratchet-plate provided with a plurality of openings to receive said horns, said horns being bent outwardly and forced against said clamp, a plate rotatably mounted on said spindle, and pawls carried by said plate to engage said ratchet-plate.

2. In a pull attachment for lamp sockets, a support arranged for attachment to the socket, a rotatable spindle carried thereby, a ratchet device rotatably secured to said spindle, a pawl device carried by said spindle to operate said ratchet device, means carried by the spindle to engage the switch mechanism of the socket, a gripping device to hold the spindle against rotation in one direction.

3. In a pull attachment for lamp sockets, a support arranged for attachment to the socket, a rotatable spindle carried thereby, a ratchet device rotatably secured to said spindle, a pawl device carried by said spindle to operate said ratchet device, a spring to keep said ratchet device and pawl device in engagement and means carried by the spindle to engage the switch mechanism of the socket, a gripping device to hold the spindle against rotation in one direction.

4. In a pull attachment for key-sockets, a support arranged for attachment to said socket, a spindle rotatably supported thereby, a spring tightly coiled around said spindle, one end of said spring being secured to said support, the other end of said spring being unsecured, said spring being arranged to grip and hold said spindle when said spindle is rotated in one direction but to permit said spindle to freely rotate when operated in the opposite direction, means to rotate said spindle, and means carried by the spindle to engage the key of the socket.

5. In a pull attachment, a rotatable spindle, means to impart to said spindle an intermittent rotary movement in one direction, and a spring coiled around said spindle and in contact therewith, arranged to grip said spindle and prevent the rotation thereof while the rotating device for said spindle is returning to its normal position.

Signed at New York city, N. Y. this 26 day of July, 1916.

PHILIP GOLATZKY.
